Fig. 2.

Fig. 8.

Fig. 2.

Fig. 9.

FIG. 1 is a top plan view of a plate for ski boots embodying my design,

FIG. 2 is a side elevational view of the plate,

FIG. 3 is a bottom plan view of the plate,

FIG. 4 is a front elevational view of the plate,

FIG. 5 is a fragmentary view on an enlarged scale of the bottom of the plate,

FIG. 6 is a view taken along the line 6-6 of FIG. 5, the view looking in the direction of the arrows,

FIG. 7 is a bottom plan view of another embodiment of such plate wherein the surface is patterned with depressions rather than arcuate grooves,

FIG. 8 is a fragmentary view in an enlarged scale of the bottom of the plate shown in FIG. 7, and

FIG. 9 is a view taken along the line 9-9 of FIG. 8, the view looking in the direction of the arrows.

This application is a continuation of my prior filed applications Ser. Nos. D. 5,900 and D. 5,901, both filed Feb. 21, 1967, now abandoned.

I claim:

The ornamental design for a plate for ski boots, as shown and described.
